United States Patent Office

Des. 176,391
Patented Dec. 13, 1955

176,391

BABY PANTS

Phyllis A. Turner, Dover, Del., assignor to International Latex Corporation, Dover, Del., a corporation of Delaware

Application July 18, 1955, Serial No. 37,019

Term of patent 14 years

(Cl. D3—17)

Fig. 1 is a front view of baby pants showing my new design; and

Fig. 2 is a plan view of the outer side thereof as they appear in unfastened position.

I claim:

The ornamental design for baby pants, as shown.
